[57] CLAIM

The ornamental design for a body for three-wheeled motor vehicle, as shown and described.

DESCRIPTION

FIG. 1 is a side elevational view of a body for three-wheeled motor vehicle showing my new design with elements of the power train shown in broken lines for illustration purposes only;

FIG. 2 is a top plan view thereof;

FIG. 3 is a bottom plan view thereof;

FIG. 4 is a front elevational view thereof; and

FIG. 5 is a back elevational view thereof.
